UNITED STATES PATENT OFFICE

ERNEST F. JUERGENSEN, OF CHICAGO, ILLINOIS, ASSIGNOR OF ONE-HALF TO
CHARLES S. BURTON, OF OAK PARK, ILLINOIS

COLUMN CLAMP

Application filed March 24, 1930. Serial No. 438,257.

This invention relates to improvements in clamps for concrete forms, and more particularly to clamps of the type adapted for firmly securing together the side panel elements constituting the forms for concrete columns and the like. An object of the present invention is to provide an improved clamp of the character mentioned which may be quickly and easily put into place for holding the form boards in close relation and also serving to reinforce the hollow column form during the pouring of the moist concrete mass, as well as while the concrete in these forms hardens. Another object resides in the provision of an improved clamp device in which the engaging parts may be continuously and uniformly advanced in minute amounts for clamping the sides of the form in close engagement with each other, and arranged for positively and firmly holding these arms in such positions of adjustment. Another object resides in the provision of an improved clamp device which is durable, simple and capable of being economically manufactured, and constructed to be quickly applied to or removed from the board panels constituting the forms, and capable of being used over again a great number of times. It consists in certain features and elements of construction, in combination, as herein shown and described, and as indicated by the claim.

In the drawing:—

Figure 1 is a fragmentary perspective view of parts of the arms of the clamp embodying my invention.

Figure 2 is a transverse section taken at line, 2—2, on Figure 1.

Figure 3 is a perspective view of my improved block.

This invention in general is similar to that disclosed in Eklof Patent No. 1,674,280 dated June 19, 1928. The clamp embodying the present invention is employed in connection with a form for a concrete column or the like which ordinarily consists of a plurality of panels, each of which may be composed of a number of boards, connected together, and reinforced by transverse cleats. These panels are positioned in such relation as to form a

hollow structure of any desired cross-section, and the panels are firmly secured in such relation by the clamp devices embodying the present invention.

The clamp is composed of a plurality of units, herein shown as two, each of which includes a pair of arms, 15, of relatively flat bar stock, which are pivotally connected together. A substantial portion of the end of each arm remote from the pivotal connection is provided with a series of longitudinally spaced elongated apertures, 17, arranged in two parallel rows with the apertures of the respective rows offset in staggered relation to each other. These clamp units are disposed with the pivot connection adjacent a corner so that the arms of each unit engage a pair of adjacent side panels, of the form, and with the adjacent arms of a pair of units, co-operating with each other to form a corner, said arms projecting beyond the intersection of the adjacent panels, transversely of each other and in overlapping relation. Slidably mounted on the end of one of the arms of each unit is a block, 35, constructed for embracing the overlapping portions of the co-operating arm.

Each of these blocks is formed with a longitudinal guideway, 36, for receiving the particular arm with which it is associated, and the inner end of this block is formed with a pair of parallel lips or flanges, 37, positioned on opposite sides of the guideway, 36, and spaced apart a proper distance so that the transversely extending co-operating arm may be positioned between these flanges, either above or below the arm on which said block is slidably disposed, which facilitates the application of the clamp to the panels of the form. The lateral portions of the flanges, 37, are preferably cut back at an angle of 45 degrees or less, as indicated at 38, so that the flanges of the respective blocks when brought in close proximity to each other (as seen in Figure 1) will not interfere with each other. The outer ends of these blocks which extend transversely of their respective arms also provide shoulders or stop surfaces, 40, adapted to be engaged by the wedge elements, of the type disclosed

in the above mentioned patent, for advancing the blocks on the transverse arms in substantially the same manner as described in said patent. By successively employing two 5 wedges 25 for engaging alternately the apertures in the respective rows in said arms the blocks may be gradually and continuously advanced by minute amounts along said arms, thereby drawing the transversely extending 10 panels of the form more closely together and into closer relation with the adjacent cooperating panels.

It has been found in using clamps of this nature to be more expedient if the movement 15 of said blocks along the two arms is effected alternatively so that the final "take-up" stresses on these arms will be about equal, thereby preventing one of the panels being forced out of position which would necessitate removal of the wedge elements 20 and separation of the cooperating arms for re-adjustment of the panels. By virtue of the elongated apertures and the wedges it is manifest that as the blocks are advanced 25 along the arms by the wedges said blocks will be definitely held in any position of advancement. This feature is of considerable importance, in that after the panels constituting 30 the form have been firmly set in position they are held in that position during the entire period of time that the form is used; i. e., while receiving the moist concrete and during the hardening of the concrete therein.

35 I claim:—

In a clamp for the purpose indicated including a pair of co-operating arms which have portions extending transversely of each other in overlapping relation to form a corner, a block for slidably mounting on each 40 of said arms constructed to embrace the other arm adjacent the overlapping portions, and means engageable with the arms and their respective blocks for advancing 45 the latter along the former and adapted for holding said blocks against outward movement on their respective arms, said blocks each having a central guideway for its arm and being provided with a pair of parallel 50 forwardly extending flanges at opposite sides of the guideway and spaced apart at a distance to form guideways between the sides of said arm and the spaced flanges for 55 accommodating the other or transverse arm in either of said last mentioned guideways.

ERNEST F. JUERGENSEN.
